UNITED STATES PATENT OFFICE.

JOHN BERRY, OF SPRINGFIELD, MASSACHUSETTS, ASSIGNOR TO THE NATIONAL NEEDLE COMPANY, OF SAME PLACE.

NEEDLE-GROOVING MACHINE.

SPECIFICATION forming part of Letters Patent No. 404,336, dated May 28, 1889.

Application filed October 29, 1888. Serial No. 289,430. (No model.)

To all whom it may concern:

Be it known that I, JOHN BERRY, a citizen of the United States, residing at Springfield, in the county of Hampden and State of Massachusetts, have invented new and useful Improvements in Needle-Grooving Machines, of which the following is a specification.

This invention relates to improvements on needle-grooving machines such as shown in the Letters Patent of the United States granted to me May 1, 1888, No. 382,250, and particularly relates, first, to means for so changing the speed of the carrier for the needle-clamping fingers that when such fingers are to present the needle clamped thereby to the rotary grooving-cutters the carrier therefore will move at a very slow rate of speed, while at the time the carrier is moved to retire the needle from the cutters after same have performed their grooving operation thereon, and to receive and re-present another needle to be grooved, its speed is considerably accelerated, whereby the machine will be capable of grooving an increased number of needles in a given time; and the invention particularly relates, secondly, to devices operating in conjunction with the needle-carrying fingers and the needle receiver and feed-way, whereby the frictional contact of the needle next behind the one clamped by the fingers upon the sides of said fingers at the time of the movement thereof, either to present or retire a needle, is avoided; and to these ends the invention consists in the construction and combination of the various parts, all substantially as will hereinafter more fully appear, and be set forth in the claims.

Reference is to be had to the accompanying drawings, forming part of this specification, in which similar characters of reference indicate corresponding parts in all the views.

Figure 1 is a side elevation of the same kind of needle-grooving machine as that described in the aforesaid Letters Patent, with the improvements of the present invention applied thereon. Fig. 2 is a plan and horizontal sectional view of parts shown in Fig. 1, as will hereinafter appear. Fig. 3 is a side elevation of the needle-carrying clamp-fingers with features of improvement in accordance with the

second part of this invention applied thereon, Fig. 4 illustrating in plan and partial horizontal section the same and a portion of the feed-way for the needle-supply, and Fig. 5 is a vertical cross-sectional view of said parts on the line $\alpha\alpha$, Figs. 3 and 4.

The main shaft 3 of the machine has on its outer end the worm-wheel 4, which is engaged by a worm-screw, 7, carried on a vertical shaft, 5, which has at its upper end a grooved driving-pulley, 6. The needle-fingers 64 and 65, to receive and clamp the needle and to discharge same, are given a reciprocating motion to the cutters and away therefrom, under the action of the cam 77 on the main shaft, 65 against the end of a sliding bar, 76, under the bed of the machine, which has a connection by a link, 78, with a vibratory lever, 75, pivoted by its lower end to a fixed arm, 74, under the machine, the upper end of the said lever 70 being connected to the needle-finger clasps, a weight, H, being applied to constantly hold the end of the bar in contact with the cam 77, all as has heretofore been made manifest by and in my said Letters Patent, and only 75 being now shown that the co-operative relations and action by the devices hereinafter described with and on said briefly-mentioned mechanism may be fully understood.

Motion is imparted to the worm-shaft 5 and 80 driving-shaft 3 at two speeds, according as the belt a from the pulley 6 is around the pulley b or the pulley d . The former, b , is fixed upon the counter-shaft f , which is driven at a comparatively slow speed, while the pulley 85 d is of sleeve form and rotates in the same direction freely on and independent of said counter-shaft f at a much greater rate of speed than said pulley b , receiving such rotation by the engagement with the pulley g , rigidly 90 fixed on its hub-extension, of a belt, h , which also passes around a pulley, j , on a counter-shaft, k , which in any suitable manner is more rapidly rotated than the counter-shaft f .

The shifting of the belt a from slow pulley 95 b to fast pulley d , or vice versa, is automatically accomplished by the movement of the intermediately-pivoted swinging shifter-lever G , having the belt-engaging hooks l at its outer end, and its inner end beyond its piv- 100

otal point *i* being located for a contact or engagement with a cam, *M*, on the face of the worm-wheel. The said cam may be a face-cam, as shown, to positively move the adjacent end of the shifter-lever in one direction, a retracting-spring effecting its reverse swing when said cam has passed out of contact; or said cam may be a grooved one, secured in the inner periphery of the worm-wheel rim, 5 within which an angular projection formed on the end of the shifter-lever might enter, in which latter instance both movements of the shifter would be positive. Said cams are to be adjustable or interchangeable, whereby 10 the relative periods of driving from said pulleys *b d* may be varied, for in forming long grooves in needles the fingers should be given the slow travel for a longer time than when short grooves were being made, and the needles require to be held to the action of the 15 cutters for a less time.

Instead of having the inner side of the lower needle clamp-finger, *64*, lie opposite to and cover for the greater portion of the time 20 the discharging end of the needle-receiver slot, as heretofore practiced, a block, *P*, is set in a horizontal dovetailed way, *p*, of the said finger *64*, and normally to be held over the discharging end of said slot, whereby 25 the said finger *64* may slide over the said block, leaving the latter to receive the impact and pressure against its side of the then foremost needle in the slot, and just before the fingers have been backed out sufficiently to bring 30 their clamping portions opposite the needle-receiver slot said obstruction-block *P* will be moved out of its position of covering for the slot, end to be returned thereto, however, after the needle-fingers have taken another needle 35 and moved inwardly therewith.

As particularly seen in Fig. 4, the block has a shoulder, *m*, at its forward end in the line of travel of and for an engagement by the shoulder *n* on the forward end portion of 40 the finger *64*, but just at the rear of the clamping-jaws. To the rear end of the said obstruction-block is pivoted a link, *q*, which at its rear end is pivotally connected to the forward 45 end of another link, *r*, which by its other end is pivoted to a stationary lug of the machine-frame.

Q represents an adjustable bar having an abutment-shoulder, *t*, toward its forward end, said bar being rigidly supported when adjusted on the finger-guiding posts *66 67*, which are movable endwise in unison with said fingers.

With the needle-fingers carried to their forward positions, as shown in Figs. 3 and 4, 55 and the said block *P* covering the end of the slot, then as the fingers are retired the one, *64*, slides by its way *p* over the said block *P* until the clamp-jaws come nearly to and opposite the end of the slot, when the block is 60 forced backward and the two connected links *q r* are forced to occupy positions about

at right angles to each other, the shoulder *t* of the bar *Q* having been passed to occupy a position at the rear of the then angularly-disposed links, so that on the next forward 70 movement of the fingers and said bar the shoulder thereof will strike and move the links forward until the said links are made to occupy angles more obtuse to each other and the apex thereof is in a lower plane 75 than the said shoulder, which passes out of contact with the links, and the movement of the block ceases, at which time it is again opposite the slot to cover same and receive 80 the impact of the needles, the bearing-pressure thereon being considerable, and which, if coming directly on the side of the moving needle-finger, would wear a groove therein and otherwise result in unsatisfactory effects 85 in the practical and continued operation of the machine.

It will of course be apparent that instead of the return of the obstruction-block *P* to its normal position by the engagement therewith of the toggle-formed links a simple retracting- 90 spring may be employed.

What I claim as my invention is—

1. In a needle-grooving machine, the main-shaft worm-wheel having the cam, and the worm-screw shaft having a pulley, the fast 95 and slow pulleys *d b*, and the belt *a*, combined with the pivoted belt-shifter by one end in engagement with said cam and by its other with said belt, whereby on the swing of the shifter by the cam the belt will be moved 100 from one of said pulleys to the other, substantially as and for the purpose described.

2. In a needle-grooving machine, the main-shaft worm-wheel having the cam *M*, and the worm-screw shaft having a pulley, the fast 105 and slow rotating counter-shafts *k f*, the pulley *b*, fixed on the latter, and the pulley *d*, loosely rotatable thereon and receiving its rotary motion from said shaft *k*, substantially as described, and the belt *a*, combined 110 with the pivoted belt-shifter by one end in engagement with said cam and by its other with said belt, all substantially as and for the purpose described.

3. The combination, with the slotted needle receiver and guide and the reciprocatory sliding clamp-finger *64*, having the way *p* and a shoulder, *n*, substantially as described, of an obstruction-block normally covering the end of the needle-receiver slot, movable in 120 said finger-way and located in the line of travel of said finger-shoulder, whereby at a period of the backward movement of said needle-finger said block will be rearwardly moved thereon, and means, substantially as described, for automatically returning said block on the forward movement of said finger, substantially as described.

4. The combination, with the slotted needle receiver and guide and the reciprocatory 125 sliding clamp-finger *64*, having the longitudinal way *p* therein and the shoulder *n*,

and carrying the shouldered abutment-bar Q, of the obstruction-block P, normally covering the end of the needle-receiver slot movable in said longitudinal way p and located in the line of travel of said finger-
5 shoulder, and the compound link q r, secured to said block and to a stationary part of the

machine, all arranged for operation substantially as and for the purpose described.
